UNITED STATES PATENT OFFICE.

JULES JOSEPH HENRI MOREL-RÉVOIL, OF PARIS, FRANCE.

SAFETY DEVICE FOR RAILWAYS.

Application filed January 21, 1926, Serial No. 82,786, and in France January 27, 1925.

The safety devices now used on railway lines comprise track apparatus which either causes the visual signs which might not be perceived by the engine driver to be repeated on the engine or else make the train stop automatically. But it is nearly impossible for the engine-driver to ascertain whilst he is driving whether this track apparatus is in good working order. Nearly all the railway accidents may be ascribed to this fact.

According to my invention the track apparatus is normally used not for stopping the train or for repeating the signals on board the engine, but on the contrary for preventing an automatic device from working, which would otherwise produce the slowing down or the stopping of the train at predetermined intervals. By means of this arrangement the defective state or working of the track apparatus has no influence on the safety of the train and only causes a supplementary stopping of the train.

The apparatus built according to my invention produces automatically stoppages of the train at predetermined intervals, whenever the action of the brake is not prevented by the action of a track apparatus over which the engine passes. The result is that the railway line is divided into a certain number of sections at the end of which the train slows down and then stops if nothing is done for making it continue its journey.

Two apparatuses embodying my invention are shown by way of example on appended drawings whereof

Fig. 1 is a diagrammatical front view of a particularly simple apparatus,

Fig. 2 is a plan view thereof.

Fig. 3 is a diagrammatical view of a second apparatus.

The simpler apparatus shown on Figs. 1 and 2 comprises a toothed wheel 1 mounted loose on a shaft 2 secured to the mechanism casing; a spiral spring 3 secured by one of its ends to the toothed wheel and by the other to the shaft 2 urges the wheel 1 in the direction of the arrow *f*. The toothed wheel bears two projections 4, 4' projecting on either side of the toothed wheel. The projection 4 is secured to the wheel by means not shown which allow its angular position to be adjusted at will. This projection 4, in a given point of its predetermined travelling path comes against a lever 5 mounted on the

shaft 2. By a lever arrangement 6 the lever 5 is adapted to control the brakes. The toothed wheel 1 is actuated by a catch 7 secured to the end of a rod 8 sliding in the slide 9. The catch 7 which acts as a driving pawl moves to and fro at regular intervals under the action of a cam 10 the rotation of which is controlled by the locomotive wheels through a suitable gearwork. A second catch or detent 11 is pivotally secured to the casing and prevents the wheel 1 when set free by the driving pawl 7 from moving backwards.

On the shaft 2 is also mounted loosely a lever 12 showing a projection 13 disposed below the catches 7 and 11 and adapted to release them. The lever 12 also bears the armature 14 of the polarized electromagnet 15 with the core of which it is normally kept in contact, the electromagnet being constantly energized by the polarizing battery diagrammatically shown at 19. The main circuit of the electromagnet is grounded and connected on the other side with a brush 16 adapted to move over a track apparatus or contact making ramp such as 18. A spring 17 weaker than the spring 3 urges the armature 14 away from its electromagnet 15.

The manner of working of the above described device is as follows:

Normally the driving pawl 7 and the detent 11 provide for a step by step motion of the toothed wheel 1. After a certain number of revolutions of the engine wheel, that is after a given distance is travelled the projection 4 arrives in front of the lever 5 and by pushing the latter provides for the braking of the train which therefore stops. But if before the two parts come into contact, the brush 16 has passed over a track apparatus 18 through which D. C. passes, the electromagnet is energized by a current stronger than and of opposite polarity with reference to that of the polarizing battery 19 whereby its action is reversed so that the electromagnet 15 lets go the armature 14. The lever 12 is raised by the spring 17 and its projection 13 lifts the catches 7 and 11. The toothed wheel 1 urged by the spring 3 rotates in the direction of the arrow *f*; the projection 4 comes back to its original position and pressing down the lever 12 obliges the armature 14 to come back against the core of the electromagnet 15, as the spring 17 is weaker than the spring 3 and the brush is no more in contact with the track ap-

paratus 18. The result is that the train is not stopped and that it may proceed on its journey until the projection 4 has travelled round up to its contact position with the 5 lever 5 or until a track apparatus again releases the catches.

The device shown on Fig. 3 is very similar to that on Figs. 1 and 2 but it provides for better results. The same parts are referred to by the same reference numbers. In this device the toothed wheel 1 is keyed to the shaft 2. The spiral spring 3 is secured by one end to this shaft and by the other to a stationary part 20. By reason of 15 the direction of its winding it urges the toothed wheel to move in the direction of the arrow *f*. The shaft 2 is provided with a square end 21 over which can be secured a cam 22 the shape of which is such as will 20 produce the desired result. In the present case, the cam shows three parts: the inner part 23 having the smallest diameter is used for the train at full speed, the intermediary part 24 of the profile is used for the slowing down and the outer part 25 showing the largest diameter for the stopping. A lever 26 pivoting round a stationary point 27 bears on the cam through a roller secured to its end. A rod 28 is pivoted to this lever and 30 controls the double regulating valve V. This valve comprises two chambers 29 and 30 the former of which is connected through a pipe 31 with the compressed air chamber. The chamber 30 is connected through the 35 pipe 32 with the brake controlling device. A tubular slide valve 33 provided with apertures 34 is adapted to slide inside the valve body and separates the two chambers 29 and 30. A piston 35 showing a circular groove 40 moves inside the slide valve and is connected with the rod 28. The slide valve 33 is pivotally secured to the levers 37 and 38; one end of the latter lever engages a groove 39 provided in a ring 40 secured to the sliding sleeve 42 of a centrifugal regulator 41. This regulator is mounted on the shaft 43 45 actuated by the driving shaft 44 of the engine.

The device works in the following manner: 50 The movement of the locomotive provides for a step by step movement of the wheel 1 as explained in connection with Fig. 1. As long as the end roller of the lever 26 bears on the part 23 of the cam the device is in its 55 normal position. After a certain time if nothing is changed, the part 24 of the cam comes under the said roller and lifts it slightly. This movement is transmitted to the piston 35 the groove 36 of which comes 60 partly in front of the apertures 34 whereby the compressed air is allowed to flow from the chamber 29 into the chamber 30 and therefrom through the pipe 32 into the brake controlling device. A certain braking effect 65 is produced and the engine slows down. If

the movement of the cam 22 continues, its part 25 comes under the roller of the lever 26. The piston 35 rises still more and its groove 36 coincides completely with the apertures 34. The air passes directly from the pipe 31 into the pipe 32 and thence into the brakes, thereby stopping the engine. 70

But if, as in the preceding case, the brush 16 has passed over a suitably excited track apparatus 18 before the part 24 of the cam arrives under the roller of the lever 26, the armature 14 is no more kept down by the electromagnet 15; the lever 12 urged by the spring 17 lifts the catches 11 and 7 so that the wheel 1 is free to rotate in the direction of the arrow *f* until the projection 4 brings the lever 12 back against the electromagnet 15 against which the armature is again kept down. The engine is allowed to continue its journey. 80

It should be noted that each time the engine stops, the engine driver must set the device back into its working position by lifting the catches 7 and 11 whereby the spring 3 is allowed to bring the cam back 85 into its original position. This can be done for instance by means of a suitable knob 50 which also controls through the rod 51 the automatic registering of the stoppages on the usual time chart actuated by clockwork 90 for the purpose of controlling the engine driver. The recording mechanism has not been illustrated as same does not form part of this invention. 95

The object of the centrifugal regulator 41 100 is to make the tubular slide valve 33 rise or sink according to the speed of the engine. To each speed of the engine corresponds a predetermined position of the slide valve and consequently a predetermined distance between the apertures 34 and the groove 36. 105

It should be noted that when the train has slowed down, the engine driver can prevent its stopping altogether. He only needs to lift the catches 7 and 11 whilst the roller of the lever 26 is still bearing on the part 24 of the cam. 110

The advantages of the device shown on Fig. 3 over that shown on Figs. 1 and 2 are 115 the following:

1. The cams 22 can be replaced easily and their profiles adapted to the kind of train which is to be protected (express, passenger, goods train) and to the distance which it is desired to travel between the moment when the device is set working and the moment it may stop the train. The profile may be such as will produce one or more slowing down periods before the train is 120 completely stopped. 125

2. The cam can be disposed outside the device whereby it can be replaced without needing to open the casing enclosing the rest of the device. 130

3. When the train travels a distance greater than has been contemplated the lever 26 lets the cam pass without being damaged whereas the lever 5 (Fig. 1) may be damaged.

In view of avoiding breakages it is of advantage to provide teeth only round part of the wheel 1 whereby the catches 7 and 11 move without actuating the wheel, when the latter is at the end of its journey, until they are set working again.

What I claim is:

1. A safety device for railways comprising an engine, a toothed wheel borne by same, a spiral spring urging same, a catch device controlled by the engine wheels and adapted to give the toothed wheel a step by step motion against the action of the spring, a part borne by the said wheel, an arrangement adapted to actuate the braking device when it is pushed by the part borne by the toothed wheel, a device adapted to release the catches from the toothed wheel a polarized electromagnet adapted when it is excited to actuate the last mentioned device and track apparatus fed with D. C. and feeding the electromagnet when the engine passes over said apparatus.

2. A safety device for railways comprising an engine, a toothed wheel borne by same, a spiral spring urging same, a catch device controlled by the engine wheels and adapted to give the toothed wheel a step by step motion against the action of the spring, a part borne by the said wheel, an arrangement adapted to actuate the braking device when it is pushed by the part borne by the toothed wheel, a lever, a projection

on said lever adapted to lift the catches away from the wheel, a weak spring urging the lever towards the catches, a polarized electromagnet adapted when it is excited to release the lever, said lever bearing normally against the electromagnet and track apparatus fed with D. C. and feeding the electromagnet when the engine passes over said apparatus.

3. A safety device for railways comprising an engine a toothed wheel borne by same, a spiral spring urging same, a catch device controlled by the engine wheels and adapted to give the toothed wheel a step by step motion against the action of the spring, a cam borne by the said wheel, a lever actuated by said cam and controlling the braking device, automatic means whereby the toothed wheel disengages its catches when the engine passes over track apparatus fed with D. C. and a knob for disengaging the catches from the toothed wheel.

4. A safety device for railways comprising an engine, a toothed wheel borne by same, a spiral spring urging same, a catch device controlled by the engine wheels and adapted to give the toothed wheel a step by step motion against the action of the spring, a cam borne by the said wheel, a lever actuated by said cam, a valve controlling the air braking device and controlled by the said lever and by a centrifugal regulator controlled by the engine wheels and means whereby the toothed wheel disengages its catches when the engine passes over track apparatus, fed with D. C.

In testimony whereof I affix my signature.

JULES JOSEPH HENRI MOREL-RÉVOIL.
